UNITED STATES PATENT OFFICE.

MILTON H. WALKER, OF NEWARK, NEW JERSEY.

TOILET KIT.

Application filed October 29, 1925. Serial No. 65,623.

This invention relates to toilet kits. The object of the invention is to provide a toilet kit, the exterior of which may be highly ornamented or formed of an expensive material, itself subject to damage by water, but at the same time to provide for the carrying and ready access in its interior of a number of toilet articles which may be removed as an entirety from the outer container. Placed on a washstand and even soaked with water without damaging the kit as a whole after the toilet articles are replaced within the outer container.

To this end, I contemplate the provision of an outer box like a container carrying an inner tray removable as an entirety and constructed of entirely water-proof material, and comprising nesting compartments for the various toilet articles. This tray may be wet, washed, and even partly filled with water, and yet when replaced in the outer container, no injury can occur to the outer container because of the fact that I provide a water-sealing cover for the removable tray, which cover automatically closes upon the tray, and protects not only clothing and other perishable articles in the valise in which the kit may be carried from injury, but also protects the outer container itself from water damage.

It is further an object of the invention to improve in general traveling kits and all of the above will better be understood and will be pointed out more fully in the accompanying claim which is directed to an illustrative embodiment of my invention described in the following specification in connection with the accompanying drawing which forms a part hereof. This illustrative embodiment is set forth merely for purposes of illustration and not limitation.

In the drawings,

Fig. 1 is a plan view of the kit with the cover open;

Fig. 2 is a vertical cross-section through the plane of II-II of Fig. 1;

Fig. 3 is a cross-section through the plane of III-III of Fig. 1; and

Fig. 4 is a perspective view of one form of the removable tray.

An outer box like container A preferably shallow is provided with a suitable hinged cover 1, which may be openable and closable,

secured by a latch 2. It is preferred that both the exterior and the interior of box A 55 and its cover 1 be covered with a highly ornamental covering such as coverings 3 for the box and 4 for the cover. This covering material may be high-grade substitute leather and even more perishable fabrics.

Within the cover 1 is preferably fixed a water-sealing closure 5, preferably of sheet celluloid, sheet bakelite, sheet leather or, in fact, any suitable truly water-proof material; and it is preferred that this sealing 65 lid be resiliently pressed outwardly from the cover portion 6 by a resilient filling 7.

Arranged to be seated within the box A is a removable tray B, having various compartments 8, designed to nest suitable toilet 70 articles indicated in dot and dash lines. It is preferred that the removable tray B project upwardly beyond the confines of the box part so as to facilitate its easy removal, but it is preferred that the outer rim 9 75 of this tray as well as most of the compartments 8 within the tray have their walls terminate flush in the same plane at the top of the tray so as to facilitate water sealing with the lid 5.

In the use of the kit, the entire tray with its contained articles is immediately removed from the box A and the tray carried to the washbasin. From its construction, it is immaterial whether the articles replaced therein, after the owner has performed his toilet, are wet or dry, and it is immaterial whether the interior of the compartments are wet or dry. Merely wiping off the exterior of the tray makes it safe for its replacement in 85 the outer container which, when closed, forms a combination wall which may be packed in a grip without danger of damaging any other articles which may be contained therein.

What I claim and desire to secure by United States Letters Patent is:

A water-proof traveling kit adapted to be carried in a traveling bag comprising a rigid outer container in the form of a box, 100 having an openable and closable cover and exteriorly capable of ornamentation; a rigid removable tray for said box formed entirely out of water-proof and water-indestructible material and having compartments respectively adapted for the nesting 105

therein of various toilet articles and substantially co-extensive with the space within said box; the outer rim of said tray and the top rims of a number of said compartments terminating substantially flush in the same top plane; and a water-proof water-sealing inner lining for the cover of said box directly

contacting with the upper rims of said tray and said compartments, and adapted to co-operate with said tray, to seal the same and 10 said compartments against the escape of water when said box is closed.

MILTON H. WALKER.
